(57) **CLAIM**

We claim the ornamental design for a header and filter access panel, as shown and described.

DESCRIPTION

FIG. 1 is a perspective view of a first embodiment of a header and filter access panel showing our new design configured for a right side mounting;

FIG. 2 is a front view of the header and filter access panel of FIG. 1;

FIG. 3 is a back view of the header and filter access panel of FIG. 1;

FIG. 4 is a left side view of the header and filter access panel of FIG. 1;

FIG. 5 is a right side view of the header and filter access panel of FIG. 1;

FIG. 6 is a top view of the header and filter access panel of FIG. 1;

FIG. 7 is a bottom view of the header and filter access panel of FIG. 1;

FIG. 8 is a perspective view of a second embodiment of a header and filter access panel showing our new design configured for a left side mounting;

FIG. 9 is a front view of the header and filter access panel of FIG. 8;

FIG. 10 is a back view of the header and filter access panel of FIG. 8;

FIG. 11 is a left side view of the header and filter access panel of FIG. 8;

FIG. 12 is a right side view of the header and filter access panel of FIG. 8;

FIG. 13 is a top view of the header and filter access panel of FIG. 8; and,

FIG. 14 is a bottom view of the header and filter access panel of FIG. 8.

The broken lines in FIGS. 1 to 14 are included for the purpose of illustrating portions of the header and filter access panel that form no part of the claimed design. None of the broken lines form a part of the claimed design. The side views of the header and filter access panel shown in FIGS. 4, 5, 11, and 12 are shown twice the size relative to the header and filter access panel shown in FIGS. 1-3, 6-10, and 13-14.
